UNITED STATES PATENT OFFICE.

WILLIS H. SARGENT, OF ST. JOHNSBURY, VERMONT, ASSIGNOR TO THE E. & T. FAIRBANKS & COMPANY, OF SAME PLACE.

DESIGN FOR A BEAM-STANDARD FOR PLATFORM-SCALES.

SPECIFICATION forming part of Design No. 33,085, dated August 14, 1900.

Application filed July 12, 1900. Serial No. 23,419. Term of patent 14 years.

To all whom it may concern:

Be it known that I, WILLIS H. SARGENT, a citizen of the United States, residing St. Johnsbury, in the county of Caledonia, State of Vermont, have invented and produced a new and original Design for a Beam-Standard for Platform-Scales, of which the following is a description, reference being had to the accompanying drawing, and to the letters of reference marked thereon.

My invention relates to a new and original design for a beam - standard for platform-scales; and it consists in the design for such herein after described, and referred to in the appended claim.

In the accompanying drawing, which illustrates the invention, the figure represents a front view of the beam-supporting standard embodying this design.

In the drawing, A represents the pillar forming part of the standard, this being of open-work construction, as shown, and having the vertically-curved portion B and the openings C. At the top and bottom the pillar is enlarged, as shown at O and D. E represents a curved bracket or brace formed at its lower end with a double scroll. The upper parts of

this scroll are connected by the bar F. Projecting upwardly and forwardly from this double scroll are curved bars G, having between and connected with them a serpentine or zigzag brace-piece H, one of said bars G at its forward end being curved around and united to the serpentine piece H, as shown at I. Projecting upwardly from the forward end of the brace is the part K, and projecting downwardly from the forward lower scroll portion is the base L. Connecting the brace-piece E and the pillar A is the part M.

The leading feature of the design consists of the pillar with the curved brace-piece.

Having thus described my invention, what I claim, and desire to secure by Letters Patent, is—

The design for a beam-standard for platform-scales, substantially as shown and described.

In testimony whereof I affix my signature in presence of two witnesses.

WILLIS H. SARGENT.
